UNITED STATES PATENT OFFICE.

EDWARD THOMAS JONES, OF NEW ORLEANS, LOUISIANA.

RADIOCONTROLLING DEVICE.

1,415,179.

Specification of Letters Patent. Patented May 9, 1922.

Application filed July 21, 1920. Serial No. 397,960.

To all whom it may concern:

Be it known that I, EDWARD THOMAS JONES, a citizen of the United States, residing at New Orleans, in the parish of Orleans and State of Louisiana, have invented certain new and useful Improvements in Radiocontrolling Devices, of which the following is a specification:

My invention relates to a switching device for controlling radio circuits, especially in regards to the transfer of the antenna from receiving to transmitting position, or vice-versa.

One object of this invention is to provide a switch having high insulating qualities confined to the switch member supports, thereby lessening the chance for leakage and reducing the manufacturing costs.

A further object is to provide a switch which can be changed from one position to another in the least possible time, thereby adding materially to its advantages over the present types employed.

A still further object of this invention is to provide a radio controlling device in the form of a switch with movable contact members taking up considerably less table space than is required by similar instruments on the present day market. This is of course a very practical and saving feature.

Cheapness of construction due to the few essential pieces or members plays an important part in addition to the features already claimed for this device.

My invention will be more clearly understood by reference to the accompanying drawings, in which—

Figure 1 shows diagrammatically one form of my switch to be used in carrying out my invention. Figure 2 shows in detail the connection of the switch members to the radio receiving and transmitting circuits.

Referring now more particularly to Figure 1, reference character 1 represents the blade of the switch; 2 the switch jaw which receives 1 when the same is brought in a downward position; 3 represents a spring contacting member which is forced apart from 2 by 1 when the latter is in a downward position. 4 and 5 are switch members which serve to open the primary power supply at the right moment, for instance, when receiving; so that transmitting cannot be effected. This protects the receiving apparatus and also the operator.

In the receiving position (when the blade

is down and between the jaws of 2) 3 is forced away from 2 upon 1 bearing down on 6 which is a small insulating bushing or stud. This is merely to disconnect the metallic circuits of the transmitter from the antenna and receiver proper. It is only necessary to have the circuit between 2 and 3 opened slightly, in fact the gap may be employed to advantage as an added protection to the receiving apparatus; forming an air gap for high potential surges which may strike the antenna while receiving, such as a bolt of lightning. The surges would traverse the small air gap in preference to the receiving inductance which offers considerable opposition to such surges.

Posts or supports, 7, 8 and 9 are composed of bakelite and are made fast to the base 10 which can be of wood, or even metal in so far as the insulation of the base is concerned, for the insulation requirements of such a device are properly taken care of by the posts 7, 8, and 9. The switch members 1, 2, and 3 are all supported at the uppermost ends of the bakelite rods. In these specifications I point out that bakelite is employed; however, any good insulating material or compound may be substituted.

The blade 1 is connected to the receiving inductance only, while the foremost end of 1 (which is 5) functions in the primary power line. It is not connected metallically to 1 but is separated and made fast to 1 by means of the small insulating strip 11. The position of the blade is manually controlled by insulated knob 12. Figure 2 shows clearly the circuits as brought to the switch members and just how the switch functions in these circuits.

What I claim is,

1. In a radio system the combination of a transmitting apparatus, an antenna system, a receiving apparatus, means connecting the antenna to said transmitting apparatus, means adapted to disconnect said connecting means, and establish connection between said antenna and said receiving apparatus, said first named means forming a protective gap across said receiving apparatus when said receiving apparatus is connected with said antenna.

2. In a radio system the combination of an antenna, a receiving apparatus, a grounding circuit, means connecting the antenna with said receiving apparatus, means adapted to disconnect said connecting means and

means associated with said grounding circuit forming a protective gap across said receiving apparatus when said receiving apparatus is connected with said antenna.

5. 3. In a radio system the combination of a transmitting apparatus, an antenna system, a receiving apparatus, means connecting the antenna to said transmitting apparatus, means adapted to disconnect said connecting means, and establish connection between said antenna and said receiving apparatus, comprising a metallic pivoted blade, a knob for manually rotating said blade about its pivot, an electrical contact carried on one end of said blade but insulated therefrom, metallic connections arranged to co-operate with said blade and contact, and a resilient member mechanically operative against said blade and adapted to form a protective gap across 45 said receiving apparatus when said receiving apparatus is connected with said antenna.
4. In a radio system the combination of a transmitting apparatus, a source of power 50 therefor, an antenna system, a receiving apparatus, means connecting the antenna to said transmitting apparatus, means connecting said source of power to said transmitting apparatus, means adapted to disconnect said connecting means and establish connection between said antenna and said receiving apparatus, said first named means forming a protective gap across said receiving apparatus when said receiving apparatus is connected with said antenna.
5. In a radio system the combination of a

transmitting apparatus, a source of power therefor, an antenna system, a receiving apparatus, an insulated support, a rotatable metallic blade pivotally mounted thereon 40 and connected with said receiving apparatus, a knob for manually rotating said blade, an electrical contact carried on one end of said blade but insulated therefrom, metallic clips arranged on opposite sides of 45 said support and adapted to receive said blade and electrical contact respectively and a resilient member mechanically operative against said blade and adapted to open the circuit from said transmitting apparatus to 50 said antenna and form a protective gap when said blade is rotated to connect said receiving apparatus with said antenna.

6. In a radio system the combination of a transmitting apparatus, an antenna system, 55 a receiving apparatus, means connecting the antenna to said transmitting apparatus, means adapted to disconnect said connecting means, and establish connection between said antenna and said receiving apparatus, comprising a pivoted blade, an insulated vertical support at the pivot thereof, a horizontal base, a knob for rotating said blade about said pivot, contacts arranged within an angle of 180 degrees and below the plane 60 of said pivot on opposite sides of said support, said blade and contacts connecting respectively the transmitting and receiving apparatus with said antenna when said knob is rotated in opposite directions.

EDWARD THOMAS JONES.
